UNITED STATES PATENT OFFICE.

ROBERT HUGH CARSON, OF DANVILLE, ILLINOIS, ASSIGNOR TO GLEN W. REED, OF DANVILLE, ILLINOIS.

CENTRIFUGAL PUMP.

1,382,604.

Specification of Letters Patent. Patented June 21, 1921.

Application filed August 19, 1919. Serial No. 318,502.

To all whom it may concern:

Be it known that I, ROBERT H. CARSON, a citizen of the United States, residing at Danville, in the county of Vermilion and State of Illinois, have invented a new and useful Centrifugal Pump, of which the following is a specification.

This invention has reference to centrifugal pumps, and its object is to provide means whereby fluid may be propelled with great force, but without the expenditure of undue power, to a destination.

While the invention is adaptable to pumping of various fluids it is particularly adapted for pumping water or other similar liquid, and, for simplicity of expression, the fluid to be pumped will hereinafter be considered as water, without the invention being necessarily confined to such particular material.

In accordance with the invention the pump comprises a stator and a rotor with the latter housed within the stator in such manner as to provide a water course from which the water under pressure is discharged. The water is drawn into the rotor and distributed to chambers therein from which the water is discharged at the periphery of the rotor through passages in trailing relation to the direction of rotation. The passages open from chambers each capable of containing a considerable amount of water whereby centrifugal force and restricted openings at the periphery of the rotor contribute to putting the bodies of water in the chambers or compartments under pressure commensurate with the speed of rotation so that high pressure at the discharge end of the pump may be obtained both because of the design of the rotor and the speed at which the latter is rotated.

The invention will be best understood from a consideration of the following detailed description taken in connection with the accompanying drawings forming part of this specification, with the understanding, however, that the invention is not confined to any strict conformity with the showing of the drawings, but may be changed and modified so long as such changes and modifications mark no material departure from the salient features of the invention as expressed in the appended claims.

In the drawings:—

Figure 1 is an elevation of a pumping

structure embodying the invention, looking toward the discharge end of the pump.

Fig. 2 is a vertical axial section of the pump omitting the driving means illustrated in Fig. 1.

Fig. 3 is a vertical section at right angles to the axis of rotation and cutting through the plane of the meeting faces of casing or stator sections.

Fig. 4 is a perspective view of the rotor 65 omitting one face plate.

Fig. 5 is a view similar to Fig. 1 but showing a somewhat modified form.

Fig. 6 is a section of the intake connection or coupling of the structure shown in 70 Fig. 5.

Referring to the drawings, there is shown a pump casing or stator A which may follow the general outlines of a centrifugal pump and comprises two sections 1 and 2 75 having flanges 3 at their meeting edges joined together by bolts 4 or otherwise, usually with interposed packing 5. In the particular showing of the drawings each section 1 and 2 is provided with a foot 6 and 80 where the pump is combined with driving means as a unitary installation, the pump casing A is mounted on a base plate 7. In Fig. 1 a pedestal 8 is erected on the base plate 7 and is provided with bearings 9 85 for a hollow shaft 10. Erected on the bearings 9 are posts 11 carrying a table 12 in turn carrying an electric motor 13 of any suitable construction. The armature shaft of the motor is provided with a pulley 14 90 from which there extends a driving belt 15 carried about another pulley 16 fast on the hollow shaft 10. The casing member 2 is provided with a journal bearing 17 carrying a gland 18 through which bearing and gland 95 the shaft 10 extends to the interior of the casing where the shaft carries a rotor B. The casing A is provided with the usual tangential outlet neck 19 to which may be attached a delivery pipe 20 to be carried to any suitable point of disposal.

The rotor B has a cylindrical peripheral portion 21 which may be made in one piece with a face plate 22 radial to the shaft 10 and forming one head of the rotor through the center of which the hollow shaft 10 opens. The rotor B is closed on the side remote from the face plate 22 by another face plate 23, which face plate is omitted in the showing of Fig. 4. It is to be un- 110

derstood, however, that the particular construction of the rotor so far described is not at all obligatory and may be varied as desired.

5 Extending radially inward from the inner wall of the peripheral portion 21 of the rotor are webs 24, which webs may be in one piece with the periphery 21 and with the face plate 22. The webs or division walls stop 10 short of the center of the rotor by a distance about equal to half the diameter of the pipe 10, although these particular dimensions are not obligatory. Each web 24 has enlargements or bosses 25 for the reception of 15 screws or bolts 26 by means of which the face plate 23 may be secured to the body portion of the rotor. At the central portion of the rotor the division plates 24 are sufficiently separated or spaced to provide ports 20 or passages 27 permitting the entrance of water from the pipe 10 into chambers 28 defined between the division walls or partitions 24 and the peripheral portion 21 of the rotor. Midway between the outer ends 25 of each partition or division wall 24 the peripheral portion 21 has ports 29 produced therethrough; these ports, which may be provided in pairs or be otherwise arranged, are inclined in a trailing direction with respect to the direction of rotation.

30 Located about intermediate of the width of the rotor is an outwardly extending rib 30 located in the course between the rotor and the inner wall of the stator or casing A. 35 This rib serves as a guide or rudder preventing any tendency of side sway and relieving the bearings of the rotor from undue strain.

30 In the showing of Fig. 1 and associated figures the shaft 10 not only serves as a shaft but as a duct for the incoming water with the shaft 10 communicating with a feed pipe 31 connected to the shaft by a packing gland 32 or in any other suitable manner. In the 45 showing of Figs. 5 and 6 a shaft 33, which may be a solid shaft, carries the rotor, and power is applied to the shaft through a pulley 16^a and belt 15^a. The casing section 1 is provided with a hub or block 34 through 50 which a hollow stub shaft 35 fast to the face plate 23 projects. The stub shaft 35 beyond the casing member 1 has an annular enlargement 36, being in the particular showing of the drawings, of angular or V-shape in cross section, whereby to provide a rib against which an elbow 37 may be applied, the elbow having a beveled or chamfered shoulder 38 to engage the neighboring portion of the 55 annular enlargement of flange 36. The 60 elbow 37 is held against the flange by bolts 39 confining packing 40 against the hub 34. In this manner the rotor may revolve in a water-tight manner, permitting ready dismantling and providing a simple construction.

When water is supplied to the rotor B it enters the chambers 28 at the axial portion thereof and fills these chambers so that the major portion of the water in the chambers is at the peripheral part thereof. Furthermore, by providing restricted outlets or ports 29 at the periphery of the rotor and about midway of the peripheral length of each chamber, the contents of each chamber are put under superior pressure. 70 The result is that jets of water issue through the ports 29 in a trailing direction into the course between the rotor and stator, with the result that there is a continued driving impulse imparted to the water, the water finding escape through the outlet neck 19.

75 The bodies of water within the compartments 28 provide mobile inertia bodies not only contributing to the momentum of the rotor but causing increased pressure through the ports 29 as the speed of the rotor increases and in this way provide correspondingly increased power or propulsion to the water being pumped.

80 In the construction shown in Fig. 1 and associated figures the effect is to provide high pressure in the delivered water while the passage of the water through the hollow shaft 10 serves to maintain the bearings 9 cool, this desirable quality being also present 85 in the bearing 17. The pump of Fig. 5 is designed more particularly for quantity pumping, delivering greater quantities of water, at low pressure under otherwise similar conditions, than occurs in the structure of Fig. 1. The course of the water through the pump is indicated in Fig. 3 by arrows 41, while the direction of travel of the rotor B is indicated by the arrow 42.

90 In the particular showing of the drawings the ports 29 are indicated as rectangular, but it will be understood they may be round, or oval, or of any suitable shape.

95 What is claimed is:—

100 1. A centrifugal pump comprising a stator and a rotor within the latter, the rotor being of substantially cylindrical form and inclosed in the stator and providing a cylindrical annular water course between them, the rotor having an exterior smooth peripheral radial rib intermediate of its width and traveling in the annular water course to serve as a guide or rudder, and said rotor having an axial inlet port and constricted outlet ports through the rotor periphery on opposite sides of the rib, and also having its interior segmentally divided between the inlet and outlet ports.

105 2. A centrifugal pump comprising a stator and a rotor within the latter, the rotor being of substantially cylindrical form and inclosed in the stator and providing a cylindrical annular water course between them, the rotor having an exterior smooth periph- 110

eral radial rib intermediate of its width and traveling in the annular water course to serve as a guide or rudder, and said rotor having an axial inlet port and constricted 5 outlet ports through the rotor periphery on opposite sides of the rib, and the interior of the rotor being radially divided.

3. A centrifugal pump comprising a stator and a rotor within the latter, the rotor containing an outwardly expanding 10 segmental compartment with an inlet means at the axial portion of the rotor and outlet ports at the peripheral portion of the compartment discharging into the space between 15 the rotor and stator, said rotor having an exterior circumferential smooth radial rib and the outlet ports trailing and located on opposite sides of the rib and intermediate of the peripheral length of the compartment.

20. 4. A centrifugal pump provided with a stator and rotor in substantially concentric relation and with the rotor within the stator, said rotor having a smooth circumferential rib or blade intermediate of the axial length 25 of the rotor and projecting into the space between the stator and rotor, said stator having segmental compartments within it with inlet ports at the axis and outlet ports 30 on opposite sides of the circumferential rib, and the peripheral portion of the rotor having the ports therethrough on opposite sides of the rib trailing and discharging into the

space between the outer wall of the rotor and the inner wall of the stator.

5. A centrifugal pump comprising a stator 35 and a rotor in substantially concentric relation, with the rotor provided with a smooth peripheral radial rib projecting from the rotor into the space between the rotor and stator, said rotor having a hollow shaft 40 supporting it and said rotor being radially divided into a plurality of substantially segmental compartments, each having an axial inlet and a peripheral outlet on each side of the rib, said outlet being located substantially 45 midway of the peripheral length of the outer end of the compartment and slanting in trailing relation to the direction of travel of the rotor.

6. A centrifugal pump comprising a stator 50 and a rotor, the rotor being concentric with the stator and provided with a cylindrical outer wall having a smooth central radial rib in the space between the rotor and stator, the rotor being interiorly partitioned 55 to form segmental compartments with the rim of the rotor provided with trailing outlet ports opening into the space between the rotor and stator and located intermediate of the peripheral lengths of the compartments. 60

In testimony, that I claim the foregoing as my own, I have hereto affixed my signature.

ROBERT HUGH CARSON.

It is hereby certified that Letters Patent No. 1,382,604, granted June 21, 1921, upon the application of Robert Hugh Carson, of Danville, Illinois, for an improvement in "Centrifugal Pumps," were erroneously issued to Glen W. Reed, as assignee of the entire interest in said invention, whereas said Letters Patent should have been issued to the inventor, said *Carson*, and *Glen W. Reed*, said Reed being assignee of *one-third* interest only in said invention, as shown by the records of assignments in this office; and that the said Letters Patent should be read with this correction therein that the same may conform to the record of the case in the Patent Office.

Signed and sealed this 23d day of August, A. D., 1921.
